Mason, Fenwick & Lawrence,

ATTORNEYS.

UNITED STATES PATENT OFFICE.

EDWIN T. KERSHAW, OF DENVER, COLORADO.

COOLING SYSTEM FOR COMBUSTION ENGINES.

Application filed October 17, 1923. Serial No. 669,133.

To all whom it may concern:

Be it known that EDWIN T. KERSHAW, a citizen of the United States, residing at Denver, in the county of Denver and State 5 of Colorado, has invented certain new and useful Improvements in Cooling Systems for Combustion Engines; and he does hereby declare the following to be a full, clear, and exact description of the invention, such 10 as will enable others skilled in the art to which it appertains to make and use the same.

This invention relates to improvements 15 in cooling systems for internal combustion engines and more particularly to that type of engine known as outboard motors which are used for driving rowboats and the like.

In accordance with this invention cooling water is supplied to the engine cylinder 20 or cylinders by means of the scoop in such a manner that water is caused to circulate when the boat to which the engine is attached is moving through the water. The invention aims to provide a cooling system of the type indicated which shall be reliable in operation and which can be manufactured at a very low cost.

Referring to the drawings,

Fig. 1 shows the stern of a rowboat 25 equipped with an outboard motor provided with the improved cooling system;

Fig. 2 is a section taken on line 2—2 of Fig. 3;

Fig. 3 is a fragmentary view in rear elevation of the motor shown in Fig. 1, the section being taken on line 3—3 of Fig. 2;

Fig. 4 is an end elevation, of Fig. 3 looking in the direction of the arrows on line 2—2 of Fig. 3, showing the preferred construction for controlling the flow of water through the circulating system, such construction taking the form of a shutter for regulating the size of the discharge orifice;

Fig. 5 shows a modified form of discharge 45 outlet.

In the drawings numeral 10 indicates a conventional rowboat or the like to which is secured an outboard motor generally indicated at 11. The motor shown is of the 50 two-cylinder type, the cylinders being indicated at 12 and disposed at either end of a yoke-like frame 13. The engine is hung on a horizontally disposed pivot 14 and 15 in-

dicates the handle by means of which the engine is tilted on the pivot 14 to properly 55 position the propeller 16.

Disposed around each engine cylinder 12 is a casing 17 which has a downwardly directed scoop 18. This scoop is of a length to project into the water and extends tangentially from the casing at the lower side of the same. The scoop and casing are conveniently made in one piece from sheet iron and the scoop is preferably of the same width as the casing to insure adequate or 65 proper circulation of the water.

The point of discharge of the cooling water may conveniently be at an axial end of the casing as indicated at 19 and the size of this opening may be regulated by a 70 shutter 20. The shutter may be held in fixed position by any suitable means as by thumb screw 21.

An alternative construction of discharge 75 for the cooling water may take the form of openings 19' stamped out of the cylindrical surface of the casing as shown in Fig. 5. Means for regulating the size of these openings may or may not be provided.

It will be understood that the size of the 80 discharge openings will regulate the rate of flow of the cooling water around the engine cylinder.

The casing 17 together with the scoop 18 is preferably adjustably mounted on the 85 engine cylinder so as to enable the scoop 18 to be positioned in the most satisfactory manner depending upon the depth of the propeller 16 in the water. The securing means may conveniently take the form of 90 straps 22 secured about the cylindrical body of the casing and having a clamping bolt and wing nut 23 associated therewith for exerting the necessary clamping action, the bolt passing through lugs 24 projecting 95 from one end of the straps 22.

The apparatus forming the cooling system of this invention is extremely simple but it is reliable in use and has the advantage of being capable of easy installation. 100 It is apparent that the detailed construction may be varied within wide limits without departing from the spirit of the invention and reference is therefore to be had to the appended claims for the scope of the invention. 105

What I claim is:

1. In combination with an outboard motor adapted to be swung about a horizontal pivot, of a scoop for conducting water to the engine cylinder, a casing surrounding the cylinder and in connection with the scoop.
2. In combination with an outboard motor adapted to be swung about a horizontal pivot, of a water casing surrounding the engine cylinder, a scoop leading from said casing and directed downwardly, said casing having an opening through which water received within the casing by means of said scoop may be discharged.
3. The combination as specified in claim
- 2 characterized by means for varying the size of the discharge opening.
4. The combination as specified in claim 2, and means for rotatably adjusting the casing on the cylinder.
5. In an outboard motor, in combination with the engine cylinder of a water casing surrounding the cylinder, a scoop extending tangentially from said casing the latter having a discharge opening at a point adjacent said scoop.
6. The combination as specified in claim 5, said scoop being as wide as the casing.

In testimony whereof he affixes his signature.

EDWIN T. KERSHAW.
